United States Patent

Des. 242,057

Patented Oct. 26, 1976

242,057

AERIAL TOY

George C. Sun, Cherry Hill, N.J., assignor to
The Amsun Corporation, Cherry Hill, N.J.

Filed July 25, 1975, Ser. No. 599,322

Term of patent 14 years

Int. Cl. D21—01

U.S. Cl. D34—15 HH

FIG. 1.
FIG. 3.

FIG. 2.
FIG. 4.

FIG. 1 is a top plan view of an aerial toy showing my new design;

FIG. 2 is a side elevational view thereof;

FIG. 3 is a bottom plan view thereof; and

FIG. 4 is an enlarged sectional view taken on lines 4-4 of FIG. 1.

I claim:

The ornamental design for an aerial toy, substantially as shown and described.
